(57) CLAIM

The ornamental design for a “toeless sock”, as shown and described.

DESCRIPTION

FIG. 1 is a top plan view of a “toeless sock” showing my new design, the bottom plan view being a mirror image thereof;

FIG. 2 is a front elevational view thereof, the rear elevational view being the mirror image thereof;

FIG. 3 is a left side elevational view thereof;

FIG. 4 is a right side elevational view thereof; and,

FIG. 5 is a prospective view of a “toeless sock” showing the same as worn on a person’s foot.

The materials shown in phantom in FIG. 5 are for environment only and are not intended to form a part of the design.
